(57) **CLAIM**

The ornamental design for a mobile card reader, as shown and described.

DESCRIPTION

FIG. 1 is a top perspective view of the mobile card reader in a non-operational configuration;

FIG. 2 is a rear view of the mobile card reader in the non-operational configuration;

FIG. 3 is a top view of the mobile card reader in the non-operational configuration, the bottom being a mirror image thereof;

FIG. 4 is a right-side view of the mobile card reader in the non-operational configuration;

FIG. 5 is a front view of the mobile card reader in the non-operational configuration;

FIG. 6 is a left-side view of the mobile card reader in the non-operational configuration;

FIG. 7 is a top view of the mobile card reader in an operational configuration, the bottom being a mirror image thereof; and, FIG. 8 is a bottom perspective view of the mobile card reader in another operational configuration.

The broken-line showing of a Universal Serial Bus (USB) male connector in the various figures and the broken-line showing of the card slots in FIG. 2 are for environmental purposes only and form no part of the claimed design.

1 Claim, 2 Drawing Sheets
